DRIVING MEANS FOR ROLLS, SPOOLS, AND THE LIKE

Hugo Wurzel, Bronx, N. Y., assignor to Waldes Kohinoor, Inc., Long Island City, N. Y., a corporation of New York

Application January 6, 1954, Serial No. 402,519

5

5 Claims. (Cl. 242—71)

This invention relates to improvements in driving means for rolls, spools and the like, and more particularly to a driving means of the type adapted to be interposed between the film-wind knob and the film-rewind roll of a loaded camera for driving the roll so as the wind up the film following each exposure thereof.

A general object of the invention is the provision of a driving means of the stated type characterized by simple and inexpensive construction and which at the same time is positive in its action and thoroughly dependable in operation.

Another object of the invention is the provision of a driving means as aforesaid, which may itself be simply assembled and disassembled, as well as one permitting easy and quick coupling and uncoupling of the film roll therewith.

A more particular object of the invention is the provision of a driving means for a camera film roll of the type employing a key shaft turnable by a film wind knob mounted externally of the camera case and a driving key carried by the key shaft and adapted to be cooperated with the film roll, wherein the driving key is in the form of a web, as distinguished from a pin, and is detachably yet effectively secured within a slot provided in the key shaft by a spring retaining ring seated in a groove therefore also provided in the key shaft.

A further object of the invention is the provision of a film roll driving means as last above characterized, wherein the spring retaining ring is operative to secure the web key against both axial and radial separation from the key shaft.

The above and other objects and advantages of a film roll driving means according to the invention will appear from the following detailed description thereof, in which reference is made to the accompanying drawings, illustrating a preferred physical embodiment thereof, wherein

Fig. 1 is a view, partly in section, looking into the film roll space of an opened camera case, which illustrates a driving means for driving the film roll contained in said space through a film wind knob mounted externally of the camera case;

Fig. 2 is a view similar to Fig. 1, but with the film wind knob and associated parts turned throughout an angle of 90°;

Fig. 3 is a side elevation of the key shaft constituting one component of the driving means of the invention, with key omitted;

Fig. 4 is a front elevation thereof;

Fig. 5 is a side elevation of a web-form of driving key according to the invention;

Fig. 6 is a front edge view thereof;

Fig. 7 is a view looking into the head or driving end of the key shaft with key assembled thereon and secured by a spring retaining ring; and

Fig. 8 is a view similar to Fig. 1 but with all parts shown in side elevation.

Referring to the drawings, reference numeral 10 designates the frame or body of a camera case, and more par-

2

ticularly the frame portion which defines and end of the film-roll space into which a film rewind roll 11 is inserted. As is usual, the roll 11 is adapted to be driven manually by a knob 12 mounted externally of the camera case and whose under face bears on a wear collar 13 affixed to the outer face of said case.

According to the invention, the knob is affixed by suitable means (not shown) to the outer end of a key shaft 15 of length to extend from the knob through the frame 10 and to project a short distance into the film roll space. As best seen in Fig. 3, the key shaft has a large diameter portion 16, a neck portion 17 of lesser diameter resulting in the formation of a shoulder 18, and a smaller diameter driving end or head portion 19 spaced axially from the neck portion by a groove 20. By reference to Fig. 2, the larger portion 16 of the key shaft extends into a closely fitting opening 22 provided therefor in the frame 10, the cylindrical wall surface of said opening thus providing a bearing for the key shaft. The shoulder 18 is so located axially in said opening that it serves as an abutment for an internal flange 23 formed on said frame to extend about the shaft opening at its inner end, the smaller diameter opening defined by said flange accommodating the neck portion 17 of the key shaft. Thus, the frame flange 23 and shaft shoulder 18 cooperate to locate the key shaft in one axial direction, i. e. by preventing inward movement of the key shaft beyond an axial position in which its shoulder engages said frame flange.

According to a further feature of the invention, the key shaft 15 is provided with a diametrical slot 24 cut through the head and neck portions and extending well into the large diameter portion thereof, and also intersecting the shaft groove 20. Such slot provides for the reception of a web key 25 which, as shown in Figs. 5 and 6, is flat and generally rectangular in shape, whereby it may be stamped from sheet metal and hardened. As best seen in Fig. 5, the key has a driving or head end 25a of appreciably greater width than the diameter of the head portion 19 of the key shaft and a seating end 25b of lesser width and which is adapted to extend into the portion of the slot 24 cutting through the large diameter portion 16 of the key shaft. In its wider end, the key is provided with opposite edge slots 26a, 26b which are spaced outwardly from its front end edge a distance corresponding to the distance that the key shaft groove 20 is spaced from the end face of the key shaft. Moreover, the slots 26a, 26b have width corresponding to the width of the key shaft groove 20, and their depth is such that the width of the key between the bottom of the slots corresponds to the diameter of the circle of the bottom of said shaft groove, although such width dimension may be slightly greater than said diameter. It will also be observed that the wider and narrower ends of the web key 25 are defined one from the other by opposite shoulders 27a, 27b which are spaced a slight distance from the slots 26a, 26b and are preferably rounded as shown. As seen in Fig. 1, the shoulders 27a, 27b, following final assembly of the key 25 in the key shaft groove 24, are adapted to abut loosely on the inner wall of the frame flange 23, thus to locate the key shaft in the other axial direction, i. e. prevent its outward movement.

A web key as described is adapted to be secured against axial and radial separation from the key shaft 15 by means of a spring retaining ring 28, preferably a so-called E ring as disclosed in United States Patent No. 2,411,761, dated November 26, 1946. Such a ring is of the open type, that is to say, a large gap is provided between its open ends whereby the ring may be assembled in its groove by simple radial deformation, and it is provided with middle and end lugs or protrusions 28a, 28b, 28c, respectively, which project inwardly from the inner edge

of the ring body, the lugs terminating in inner arcuate edges which lie on a circle of somewhat smaller diameter than that of the circle of the bottom of the groove in which the ring seats, whereby, when assembled in its groove, the ring secures itself with spring pressure.

Thus, according to the invention, a web key such as the key 25 may be located and secured to the key shaft 15 simply by inserting the narrow end 25b of the key shaft into the shaft slot 24 to a depth such that the key slots 26a, 26b line up with the shaft groove 20 and thereupon assembling, the retaining ring 23 in said groove in the usual manner. During such assembly, at least the ring end lugs 28b, 28c move into the key slots 26a, 26b and thereby securely lock the key in operating position to the key shaft. When it is desired to remove the key from the key shaft for repair or replacement purposes, such may be effected simply by disassembling the retaining ring 28 from the shaft groove 20 in the usual manner, whereupon the key may be simply withdrawn from the key slot 24. It is a further feature of the invention that upon removal of the key from the key shaft the entire key shaft assembly may be disassembled from the camera simply by pull exerted on the knob 12.

Due to the width of the wider end 25a of the web key being greater than the diameter of the head end 19 of the key shaft, the side edges of the key extend radially from the latter, as shown in Figs. 7 and 8. Such extending side edges serve as diametrically opposed driving wings projecting radially from the driving or head end of the key shaft and are thus capable of driving a member provided with a suitably shaped key-hole which is co-operated therewith.

Referring to Fig. 1, the end disc 11a of the film roll 11 is provided with a key-hole 11b shaped complementally to the head end 19 of the key shaft and the aforesaid driving wings provided thereon by the extending side edges of the key 24. Thus, the film roll may be simply coupled to the key shaft by moving it to a position such that the driving end of the key shaft enters the key hole 11b whereupon the roll may be driven by manual rotation of the knob 12, and uncoupling of the film roll may be effected in equally simple manner merely by moving the roll axially away from the key shaft.

Without further analysis, it will be seen that the film roll drive described above achieves the objectives therefore outlined in the foregoing. That is to say, the web-form driving key employed in such a drive gives more positive action than the prior pin-form driving key, and its construction, as well as that of the key shaft, is such that it may be assembled with the key shaft and disassembled therefrom in exceedingly simple manner. Moreover, a driving means according to the present invention is capable of being assembled and disassembled as a whole from the camera, thus permitting easy repair and/or replacement when such is required. Finally, the driving means of the invention may be inexpensively manufactured, and its initial assembly costs are low as compared to those involved with prior film roll driving means.

As many changes could be made in carrying out the

above construction without departing from the scope of the invention, it is intended that all matter contained in the above description or shown in the accompanying drawings shall be interpreted as illustrative and not in a limiting sense.

1 claim:

1. Means for driving a camera film roll from a film wind knob mounted externally of the camera comprising, in combination, a key shaft extending through an opening in the frame and being affixed at its outer end to said knob, the key shaft being provided adjacent its inner end with a circular groove and having a diametrical through slot intersecting said groove, a web-form driving key received in said slot, and an open-ended spring retaining ring seated in said groove and coacting with said key to secure it against both axial and radial displacement.

2. Driving means as set forth in claim 1, wherein said key is provided in its opposite edges with slots shaped and positioned so as to register with said groove and through which the ring extends.

3. Driving means as set forth in claim 1, wherein said key shaft and said key are each provided with means which operate conjointly to secure the key shaft against axial displacement.

4. Driving means as set forth in claim 1, wherein said key shaft and said key are provided with facing shoulders providing axially spaced abutments for means on the frame, said abutment means preventing axial displacement of the key shaft relative to frame.

5. Means for driving a camera film roll from a film wind knob mounted externally of the camera comprising, in combination, a key shaft extending through an opening in the frame and being affixed at its outer end to said knob, the key shaft having a large diameter outer end portion separated from a smaller diameter inner portion by a shoulder located near the inner end of said opening and which abuts the outer side of an internal frame flange extending along said opening at its inner end, the inner end portion of the key shaft being provided with a circular groove and both said outer and inner end portions having a diametrical slot cutting through said groove, a web-form key received in said slot and having one end portion of greater width than the diameter of said inner end portion whereby its side edges extend radially therefrom, the other end portion of said key extending into and being contained within the circumference of the larger diameter end of the key shaft, said radially extending side edges of the key being provided with opposite slots disposed in registry with the groove, a spring retaining ring seated in the groove and passing through said opposite slots, said radially extending side edges terminating in outwardly facing shoulders which abut the inner side of said internal frame flange.
